TELEVISION CABINET OR SIMILAR ARTICLE

Joseph D. Portanova, Arcadia, and John Stevens, Downey, Calif., assignors to Hoffman Radio Corporation, a corporation of California

Application April 15, 1954, Serial No. 30,035

Term of patent 14 years

(Cl. D56—4)

The rear of the cabinet is plain and unornamented.

The essential features of our design reside in those portions shown in full lines.

We claim:

The ornamental design for a television cabinet or similar article, substantially as shown and described.
